his Atty.

UNITED STATES PATENT OFFICE.

JAMES A. WRAY, OF CHICAGO, ILLINOIS.

SQUARE.

SPECIFICATION forming part of Letters Patent No. 680,830, dated August 20, 1901.

Application filed July 5, 1900. Serial No. 22,546. (No model.)

To all whom it may concern:

Be it known that I, JAMES A. WRAY, a citizen of the United States, residing at Chicago, in the county of Cook and State of Illinois, 5 have invented certain new and useful Improvements in Squares, of which the following is a specification, reference being had to the accompanying drawings.

My invention relates to separable squares, 10 and has for its object to provide a new and improved construction of separable squares in which the parts of the square are firmly secured together, but may nevertheless be readily separated when desired. I accomplish this object as hereinafter specified and as illustrated in the drawings.

That which I regard as new will be set forth in the claims.

Referring to the drawings, Figure 1 is a 20 plan view of the square. Fig. 2 is a section on line 2 2 of Fig. 1 inverted. Fig. 3 is a section on line 3 3 of Fig. 1 inverted. Fig. 4 is a section on line 4 4 of Fig. 1 inverted. Fig. 5 is an enlarged detail illustrating the operation of the locking devices. Fig. 6 is a similar view, and Fig. 7 is a section on line 7 7 of Fig. 5.

The square is composed of two arms 8 9, respectively, the arm 8 being straight and being provided near one end with a broad channel having rabbet-grooves 10 11 at its edges, as shown in Fig. 3. The groove 10 extends to the end of the arm 8, as illustrated in dotted lines in Fig. 1; but the groove 11 terminates at a point 12, removed from the end of said arm by the width of the arm 9, as shown in dotted lines in Fig. 1. This is due to the fact that the metal of the arm 8 from the point 12 to the adjacent end of the arm is cut 35 away, so that the tongue of the arm 9, herein-after described, may be fitted to the arm 8 and lie flush with the surface thereof. The inner side edge of the arm 8 from the point 12 to the adjacent end thereof is beveled, as shown at 13 in Fig. 2, for a purpose herein-after set forth.

As shown in Fig. 1, the arm 9 is provided with a tongue 14, arranged at right angles thereto, the thickness of said tongue being 50 such that when it is fitted in the channel in the arm 8 its surface is flush with the surface of said arm. Said tongue is of suitable

width to fit in said channel and is provided at its edges with ribs or tongues 15 16, which fit in the rabbet-grooves 10 11. The end of 55 the tongue 14 preferably is rounded, as shown in Figs. 1, 5, and 6, and fits closely to the inner end of the channel, which is of corresponding shape. The tongue 14 is formed by cutting away the under side of the arm 9 to 60 make the tongue of proper thickness, and that portion of the arm 9 which lies opposite the beveled edge 13 of the arm 8 is undercut or is provided with a dovetailed groove 17, as shown in Fig. 2, so that when the parts are 65 fitted together the edge 13 of the arm 8 slides in the groove 17 of the arm 9, as shown in Fig. 2.

When the parts are assembled, the ribs 15 16 at the edges of the tongue 14 enter the grooves 70 10 11, respectively, the tongue 14 being moved lengthwise into the channel in the arm 8. When the tongue 14 has been moved far enough, the beveled edge 13 enters the groove 17 and moves into said groove until the tongue 75 14 has moved entirely into its socket, when the parts will be in the position shown in Fig. 1. By this construction the arm 9 engages the arm 8 at both sides or surfaces thereof, securing a very firm union of the parts, as is 80 necessary in an instrument of this character. In order to prevent the accidental displacement of the parts of the square, a locking device is provided, consisting of a screw 18, fitted in a suitable socket in the arm 8 near one 85 edge of the channel therein, said screw projecting into one of the rabbet-grooves, as 10. (See Fig. 5.) Said screw is provided with a cut-out portion 19, which may be turned into alinement with the rabbet-groove 10 by turning the screw, and when in such position forms a part of said groove and does not interfere with the movement of the tongue 14 therein. Said tongue is provided with a concave recess 20 in one of its edges, so placed that when the 95 tongue 14 is in its innermost position said recess will lie opposite the screw 18, as shown in Fig. 5.

When assembling or separating the parts, the screw 18 is turned to the position shown 100 in Figs. 4 and 6, the cut-out portion 19 being then in alinement with the groove 10, permitting the tongue 14 to move in or out, as the case may be. When the parts have been

fully assembled, the screw 18 is turned to the position shown in Fig. 5, causing a portion of the screw to project into the recess 20, thereby effectually locking the tongue 14 5 in place. The screw 18 is provided with a slot 21, so that it may be conveniently turned.

I do not wish to limit myself to using rabbeted grooves 10 11, as dovetailed or other equivalent grooves may be used, and instead 10 of using a dovetailed groove 17 and a beveled edge 13 a rabbet-groove with a corresponding tongue at the edge of the arm 8 may be employed.

That which I claim as my invention, and 15 desire to secure by Letters Patent, is—

1. A separable square composed of two members, one having a channel on one surface, extending longitudinally of said member and formed with grooves along its sides, 20 one side of said channel terminating at the end of the member in which it is formed and the other side at a point a short distance from said end, and the other member having a tongue on one surface adapted to fit in said 25 channel and whose side edges are adapted to fit in said grooves.

2. A separable square composed of two members, one having a beveled side edge on one surface and a channel on the other surface, 30 extending longitudinally of said member and having grooves along its sides, one side of said channel terminating at the end of the member in which it is formed and the other side at a point a short distance from 35 said end, and the other member having a groove on one surface adapted to receive said beveled edge and having a tongue on the other surface adapted to fit in said channel and whose side edges are adapted to fit in the 40 grooves along the sides of said channel.

3. A separable square composed of two members, one having a rabbeted channel on one surface, extending longitudinally of said member, one side of said channel terminating 45 at the end of the member in which it is formed and the other side at a point a short distance from said end, and the other member having a tongue on one surface whose side edges are formed with ribs adapted to 50 fit in the rabbet-grooves along the sides of said channel.

4. A separable square composed of two members, one having a beveled side edge on one surface and a rabbeted channel on the 55 other surface, extending longitudinally of said member, one side of said channel terminat-

ing at the end of the member in which it is formed and the other side at a point a short distance from said end, and the other member having a groove on one surface adapted 60 to receive said beveled edge and having a tongue on the other surface whose side edges are formed with ribs adapted to fit in the rabbet-grooves along the sides of said channel.

5. A separable square composed of two members, one having a rabbeted channel on one surface, extending longitudinally of said member, provided with a rounded end and having one side terminating at the end of the 70 member in which it is formed and the other side at a point a short distance from said end, and the other member having a tongue on one surface whose end is rounded and whose side edges are formed with ribs, the rounded 75 end of said tongue adapted to fit in the rounded end of said channel and said ribs adapted to fit in the rabbet-grooves along the sides of said channel.

6. A separable square composed of two 80 members, one having a channel on one surface, extending longitudinally of said member and formed with grooves along its sides, one side of said channel terminating at the end of the member in which it is formed and 85 the other side at a point a short distance from said end, and the other member having a tongue on one surface adapted to fit in said channel and whose side edges are adapted to fit in said grooves, and means for locking the 90 two members against accidental separation.

7. A separable square composed of two members, one having a beveled side edge on one surface and a channel on the other surface, 95 extending longitudinally of said member and having grooves along its sides, one side of said channel terminating at the end of the member in which it is formed and the other side at a point a short distance from said end, and the other member having a 100 groove on one surface adapted to receive said beveled edge and having a tongue on the other surface adapted to fit in said channel and whose side edges are adapted to fit in the 105 grooves along the sides of said channel, and means for locking the two members against accidental separation.
